UNITED STATES PATENT OFFICE.

LEE CHANDLER, OF OKLAHOMA, OKLAHOMA, ASSIGNOR OF ONE-HALF TO JOHN D. ALLEN, OF OKLAHOMA, OKLAHOMA.

APPARATUS FOR PAINTING SMOKESTACKS.

1,345,834.

Specification of Letters Patent.

Patented July 6, 1920.

Application filed November 3, 1919. Serial No. 335,489.

To all whom it may concern:

Be it known that I, LEE CHANDLER, a citizen of the United States, residing at Oklahoma, in the county of Oklahoma and State of Oklahoma, have invented certain new and useful Improvements in Apparatus for Painting Smokestacks, of which the following is a specification, reference being had to the accompanying drawings.

10 The object of the invention is to provide safe and convenient means for painting smoke stacks.

Referring to the six figures of the drawings:

15 Figure 1 is a plan view of a smoke stack with the improved apparatus installed thereon, no parts being shown below the line 3—3 of Fig. 2.

Fig. 2 is an elevation view.

20 Fig. 3 is a sectional view taken on the line 3—3 of Fig. 2, with a rope and weight omitted and with no parts shown below the line A—A.

Fig. 4 is an elevation view in the direction of the arrow 4 of Fig. 2.

Fig. 5 is a perspective view of a vertically movable brush and paint container, together with parts for controlling the flow of paint which are not shown in Figs. 1 to 4.

30 Fig. 6 is an elevation view of the parts shown in Fig. 5 and a small fragment of the smoke stack, a portion of the paint container being broken away to expose an outlet opening.

35 Like characters of reference designate like parts in all the figures.

In arranging the improved apparatus, a bridge-bar 10 is extended diametrically across the upper end of the stack 11 and permanently riveted to said stack to support an upstanding spindle 12.

A triangular skeleton crane 13 is mounted on top of the stack 11 and arranged to be revolved in a horizontal plane.

45 This crane 13 includes a plate 14 which is permanently pivoted to the upper end of the spindle 12; two divergent strap-iron members 15 which radially overhang the stack 11; a flat horizontal plate 16 connecting the central portions of the members 15; and a strap-iron bar 17 connecting the outer ends of said members 15; all these

parts being securely riveted together as shown.

The crane 13 is supported centrally by two rollers 18 whose frames 19 are secured to the underside of the plate 16, these rollers being adapted to travel on the upper edge 20 of the stack 11 when the crane is revolved around the spindle 12.

In order that the upper edge 20 of the stack 11 shall form a durable track for the rollers 18, it may be reinforced and widened by a strap-iron band 21 which is extended around on the outside of the stack and securely riveted.

Two guiding cables 22 are suspended from the crane 13, one of the cables being suspended from one of the members 15 and the other cable from the other member.

70 Each cable 22 has its lower end attached to a windlass shaft 23 so that it may be individually drawn taut.

The outer ends of the two shafts 23 are journaled in the outer ends of projecting arms 24 which are in turn riveted to and supported by a band 25 which embraces the lower portion of the stack 11; and the adjacent ends of said shafts are supported by extending revolvably into a central sleeve 26 as best shown in Fig. 3.

75 The arms 24 are braced to the band 25 by a strap-iron bar 27; and said band, bar, and arms are all securely riveted together.

The ends 28 of the band 25 are turned outward and secured together by a take-up screw 29.

80 The windlass shafts 23 are provided with cranks 30 and ratchet-wheels 31, and after the cables 22 are drawn taut by said shafts the latter are held by detents 32 which are pivoted to the arms 24 and engage said ratchet-wheels.

A container 33 for paint or other liquid preparation is arranged to be guided in its vertical movements by the cables 22 and is provided on its ends with sleeves 34 through which said cables slidably pass.

85 A suitable brush 35 is positioned below the container 33 and arranged to travel therewith, the head-piece 36 of the brush being secured by screws 37 to the lower edge of a metal plate 38 which is in turn soldered to the container 33.

In the simple arrangement of the container 33 and brush 35 shown in Figs. 1, 2, and 4, the container is provided in its lower wall with one or more outlet openings 39, like the opening 39 shown in Fig. 6 but much smaller and permanently open; and in using the apparatus the paint 40 flows slowly and continuously down through the openings onto the brush and is applied to the stack 11 by moving the brush upward and downward in contact therewith.

For moving the brush 35 and container 33 in spreading the paint, a rope 41 is hitched to the upper portion of the plate 38 and passes up over a pulley 42 secured to the bar 17 of the crane 13, said rope passing thence downward to within convenient reach of an operator and back upward, and being hitched to the lower edge of the plate 38 as shown in Fig. 2.

To keep the rope 41 from swinging too loosely it is passed under a pulley 43 from which a weight 44 is suspended; and with the rope arranged in this way the brush 35 and container 33 may be drawn repeatedly up and down the stack 11 to thoroughly apply a coat of paint.

The container 33 shown in Figs. 5 and 6 is provided toward each of its ends with the opening 39, aforesaid, and each opening is closed by a valve 45 which is mounted on a lever 46.

Each lever 46 is fulcrumed to a lug 47 fixed rigidly on the container 33 on the side opposite the plate 38, said lever extending under the container and through a vertical slot 48 in said plate.

Each lever 46 is normally held upward at its free end by a tension spring 49 to seat its valve 45 against the opening 39 of the container 44, the upper end of each spring being hitched to a staple 50 on the upper edge of the plate 38.

For opening the valves 45, that portion 51 of the rope 41 extending upward from the pulley 43 of the weight 44 is hitched to the center of an equalizing bar 52, one end of said bar being connected to one lever 46 by a rod 53 and the other end to the other lever 46 by a similar rod 53.

The weight 44 may be raised upward and its hook 54 caught over some supporting part of the apparatus, for example over the sleeve 26 of the windlass shafts 23; and the springs 49 are strong enough to keep the valves 45 tightly closed against any pull on the rope 41 commonly required to draw the brush 35 and container 33 downward.

In use, it is possibly preferable to start the brush 35 at the lower part of the stack 11 so that the upward wipe will bend its bristles downward and allow the paint to gravitate toward their delivery ends; and in starting the brush upward the weight 44 may be unhooked from the sleeve 26 and al-

lowed to put the rope 41 under tension to open the valves 45 and release the paint from the container 33.

When the brush 35 has arrived at the top of the stack 11 the weight 44 may again be hooked up to allow the valves 45 to close for a downward or return stroke of the brush 35.

After each stroke of the brush 35, the screw 29 of the band 25 may be loosened and said band and attached parts may be revolved around the stack to position to start the next stroke of the brush; the crane 13 at the upper end of the stack being swung around by a sharp lateral jerk on the rope 41.

After the stack 11 has been painted the cables 22 may be detached from the shafts 23 and allow the container 33 to be removed from them, the upper ends of these cables remain permanently attached to the crane 13.

The rope 41 may also be unhitched from the container 33 and the ends of said rope may be tied together to keep it from passing out of the upper pulley 42.

The crane 13 at the top of the stack 11, and the band 25 and attached parts at the lower part of the stack, may remain permanently in place.

The painting may be done without climbing the stack and without danger.

The following is claimed:—

1. In apparatus of the class described, an overhead support, a guiding cable suspended from the support, a paint container arranged to slide along the cable, means for sliding said container, a paint brush attached to the container, and means operable by the sliding means for releasing paint from the container onto the brush.

2. In combination with a smoke stack, a guiding cable suspended from the top of the stack, a paint container arranged to slide along the cable, a paint brush attached to the container, manually operable suspending means adapted to support the container and slide it along the cable, and means operable by the suspending means for releasing the paint from the container onto the brush.

3. In combination with a smoke stack, a guiding cable suspended from the top of the stack, a paint container arranged to slide along the cable, a paint brush attached to the container, a pulley suspended at the top of the stack, a rope passing over said pulley and having both of its ends attached to the container, and means whereby a predetermined amount of pull on the rope releases paint from the container onto the brush.

4. In combination with a smoke stack, a guiding cable suspended from the top of the stack, a paint container arranged to slide along the cable, a paint brush attached to the container, a pulley suspended at the top of the stack, a rope passing over said pulley and having both of its ends attached to the

5 container, means whereby a predetermined amount of pull on the rope releases paint from the container onto the brush, and means for varying the amount of pull on the rope.

5. In combination with a smoke stack, a supporting crane pivoted to the top of the smoke stack and arranged to be revolved in a horizontal plane, a band embracing the

lower portion of the stack and adapted to be revolved around the stack, guiding cables extending from the crane down to the band, and means adapted to slide along said cables to apply paint to the stack.

Witness my hand this 12th day of September, 1919.

LEE CHANDLER.
